PISTON RING

Harford L. Morgan, San Francisco, Calif.

Application April 24, 1936, Serial No. 76,179

7 Claims. (Cl. 309—43)

The present invention relates to improvements in piston rings and its principal object is to provide a piston ring that is particularly well adapted to serve the purpose of maintaining compression, has an easy gliding fit with the wall of the cylinder and long wearing qualities.

More particularly it is proposed to provide a split piston ring with an inner spring for expanding the ring, the latter being preferably tensioned so as to normally close at the split and to cause the spring to become the sole or main expanding factor in the assembly.

It is further proposed to use a split expansion spring of the serpentine or polygonal type and to arrange the ring in such a manner that the ends of the spring are prevented from accidentally projecting through the split of the ring and from scraping the cylinder wall.

It is further proposed, in a modified form, to construct the ring of two split sections, one lying on top of the other, with the splits in non-registering relation, but with anchoring means for the spring arranged in registering relation.

It is further proposed to provide the piston ring, whether made in one or two sections, with an inner groove for receiving the projecting portions of the serpentine or polygonal spring and to step the side walls of the groove so as to allow of free play of the spring within the groove.

Further objects and advantages of my invention will appear as the specification proceeds.

The preferred forms of my invention are illustrated in the accompanying drawing in which

Figure 1 shows, in vertical section and in fragmentary view, the relative arrangement of my piston ring and the piston and the cylinder wall.

Figure 2 a top plan view of one form of piston ring made in accordance with my invention the ring being shown as being under compression,

Figure 3 a sectional view taken along line 3—3 of Figure 2,

Figure 4 a sectional view taken along line 4—4 of Figure 2,

Figure 5 a plan view of a modified form of my piston ring comprising two sections, a portion of the upper section being removed to show the lower section and the ring being shown as being under compression,

Figure 6 an inside view of the removed portion 50 of the upper section,

Figure 7 a sectional view taken along line 7—7 of Figure 5, and

Figure 8 a sectional view through the piston ring taken along line 8—8 of Figure 5.

While I have shown only the preferred forms

of my invention I wish to have it understood that various changes or modifications may be made within the scope of the claims hereto attached without departing from the spirit of the invention.

Referring to the drawing in detail it will be seen that Figure 1 shows the conventional arrangement of the piston 1 having slight clearance relative to the cylinder wall 2 and being provided with an annular groove 3 for accommodating the piston ring 4. The latter which is illustrated as one form of my invention in Figures 2, 3 and 4, is of the solid type, that is, made in one piece and is split as at 5.

The ring is made of elastic material and its tension is preferably such that it is normally closed at the split, without leaving a gap. The ring is formed with a central groove 6 in the inner face thereof, the groove being rectangular in cross-section and the side walls of the groove 20 being stepped away from the center line of the groove as shown at 7 to provide greater clearance for the spring 8 accommodated in the groove.

The spring is preferably polygonal or serpentine in form and its outer corners 9 are received in the groove, the width of the spring corresponding substantially to the width of the bottom of the groove so that the extreme corners of the spring have a sliding fit therein while the stepped side walls allow greater clearance adjacent the corners. The spring is split and is of such length that when properly positioned in the groove, the free ends 10 of the spring leave a gap and are disposed on opposite ends of stops 11 formed in the groove on opposite sides of the split so that

any considerable lengthwise or rotary movement of the spring is prevented. The stops are formed by making the ring of solid rectangular cross-section as shown in Figure 4. The spring has a natural tendency to open the ring and to expand 40 the same against the cylinder wall.

The bottom face of the piston ring is preferably formed with a slanting recess 12 to provide a sharp edge for scraping any oil that might attempt to pass the ring on the downward stroke 45 of the piston.

A modified and preferred form of the invention is shown in Figures 5—8 in which the ring is made of two sections 13 and 14, the former overlying the latter. The two sections are split as shown at 50 15 and 16 and the two splits are arranged in non-registering relation, preferably diametrically opposite one another, as shown in Figure 5. The sections are formed with annular recesses 17 and 18 which cooperate in forming an annular groove 55

19 corresponding to the groove 6 of the solid piston ring. The side walls of this groove are also stepped as shown at 20.

This groove is also formed with stops for limiting spring movement, the stops in the lower section being disposed on opposite sides of the split 16 as shown at 21 and a registering stop 22 being formed in the upper section diametrically opposite its split 15, each stop being made to completely 10 fill the groove so that at the stop each section is rectangular in cross-section or end-view as shown in Figure 7.

The spring 23 is substantially the same as the spring 8 previously described and its free ends 24 15 are limited in their movement by the stops 21 and 22 respectively.

In this form the ring sections 13 and 14 are also made of elastic material and are tensioned so as to normally close at their splits 15 and 16, while 20 the spring tends to expand the ring against the cylinder wall.

This form of my ring has the advantage that due to the non-registry of the splits in the two sections no gap is formed when the ring is expanded. It is also more sensitive and responsive 25 to the spring action since each section is thinner and more flexible than the solid ring of the first form.

I claim:

30 1. A piston ring comprising two split ring sections arranged one on top of the other with the splits in non-registering relation, the sections having annular recesses cooperating in forming an inner annular groove in the piston ring and having registering stops blocking a limited portion 35 of the groove and a split polygonal spring seated in the groove and having its ends confronting opposite sides of the stops.

2. A piston ring comprising two split ring sections arranged one on top of the other with the splits in diametrically opposite relation, the sections having annular recesses cooperating in forming an inner annular groove in the piston ring and having registering stops at one of the splits for blocking a limited portion of the groove 45 and a split polygonal spring seated in the groove and having its ends confronting opposite sides of the stops.

3. A piston ring comprising two split ring sections arranged one on top of the other with the splits in non-registering relation, the sections having annular recesses cooperating in forming

an inner annular groove in the piston ring and having registering stops blocking a limited portion of the groove and a split expansion spring seated in the groove and having its ends confronting opposite sides of the stops.

4. A piston ring comprising two split ring sections arranged one on top of the other with the splits in non-registering relation, the sections having annular recesses cooperating in forming an inner annular groove in the piston ring and having registering stops blocking a limited portion of the groove and a split expansion spring seated in the groove and having its ends confronting opposite sides of the stops, the ring sections being tensioned to normally close at the 10 splits so as to throw the burden of expanding the ring entirely on the spring.

5. A piston ring comprising two split ring sections arranged one on top of the other with the splits in non-registering relation, the sections having annular recesses cooperating in forming an inner annular groove in the piston ring and having registering stops blocking a limited portion of the groove and a split expansion spring seated in the groove and having its ends confronting opposite sides of the stops, the side walls of the groove being stepped back from the center-line of the groove to facilitate free play of the spring in the groove.

6. In combination, a split piston ring having an 30 annular groove in the inner surface thereof and a polygonal spring having its corners seated within the groove and being tensioned for expanding the ring, the width of the spring being substantially equal to that of the groove and the side walls of 35 the groove being stepped back from the spring intermediate their height to facilitate free play of the spring within the groove.

7. In combination, a split piston ring having an 40 inner annular groove and stops in the groove on opposite sides of the split and a split polygonal expansion spring having its corners seated in the groove and its ends disposed on opposite sides of the stops, the splits in the ring and in the spring being made to register to co-relate expansive play 45 of the spring with responsive flexing of the ring and the side walls of the groove being stepped back intermediate their height to clear the spring for free play immediately adjacent the corners of the spring.

HARFORD L. MORGAN.
